(57) CLAIM

I claim the ornamental design for a plush star belly unicorn, as shown and described.

DESCRIPTION

FIG. 1 is a front perspective view of a plush star belly unicorn;

FIG. 2 is a front view of the plush star belly unicorn of FIG. 1;

FIG. 3 is a rear view of the plush star belly unicorn of FIG. 1;

FIG. 4 is a left side view of the plush star belly unicorn of FIG. 1;

FIG. 5 is a right side view of the plush star belly unicorn of FIG. 1;

FIG. 6 is a top view of the plush star belly unicorn of FIG. 1; and,

FIG. 7 is a bottom view of the plush star belly unicorn of FIG. 1.

The broken lines in the drawings illustrate portions of the plush star belly unicorn that form no part of the claimed design. The dot-dash-dot broken lines in the figures depict boundaries of the claim that form no part thereof.

1 Claim, 7 Drawing Sheets
